MANUFACTURING OF FRAMES FOR HAND MIRRORS OR THE LIKE

Alfred F. Reilly, North Attleboro, Mass., assignor to Evans Case Company, North Attleboro, Mass., a corporation of Massachusetts

Application November 10, 1936, Serial No. 110,159

6 Claims. (Cl. 113—116)

In general the invention relates to the manufacture of a frame or back or holder consisting in its final form of a sheet or plate having a turned up periphery the edge of which is turned in. Such frames frequently are provided with similarly constructed handles generally made integral therewith. Such frames may hold mirrors, brushes or other devices.

For illustrative purposes the invention will be shown and described as applied to a backing for a hand mirror of one particular shape. It will be understood, however, that the shape of the hand mirror or frame is not of the essence of the present invention.

When such devices are made of metal turned up at the edge and then turned in the expense and difficulty of manufacture are enhanced by the fact that the turning and straining of the metal weakens it and may cause cracks or openings at the turned corners. Such a defect destroys the whole frame which may not be used. A purpose of the present invention is to construct such a frame of assembled metal parts associated in such a way as to have substantially no tendency to distort, crack or split the metal. To this end a sheet of more or less flat metal may be stamped to the form and shape desired for the back of the article. This flat sheet may be ornamented as it is cut or afterward. It may remain a flat sheet or portions may be lifted for ornamental or other purposes. Metal in channel form may then be cut the proper length and shaped to approximately the contour of the stamped back. While a single piece of channel may be employed for this it is preferable to make it of several pieces the ends of which will of course be properly mitered to make a close, neat fit when assembled and applied to the edges of the cut flat sheet. They may thus be permanently held in place by spot welding or otherwise attaching to the sheet. A second smaller flat sheet may be provided to be applied to the open side of the channel members applied to the handle and this may be held in place by soldering, welding, brazing or in any other suitable manner. It will be understood that such a construction employing metal in standard forms makes a cheaper and simpler article and by obviating the necessity for complicated pressing drawing or turning avoids the likelihood of numerous defects during the manufacturing operation.

In the accompanying drawing Figure 1 is a plan view of a finished frame or holder for a hand mirror. Fig. 2 is a transverse section on the line 2—2 of Fig. 1 on an enlarged scale. Fig.

3 is a perspective view of the frame showing the back plate and the channel members assembled but before the closure for the handle has been applied. Figs. 4, 5, 7, 8, and 9 are plan views of portions of the channel members. Fig. 5 is a plan view of the stamped back member and Fig. 6 is a plan view of the cover for the handle extension. The back member may be stamped in any suitable shape. In the drawing a back member 15 is illustrated having a round head portion from which extends a straight sided handle. This may be made plain or may be provided with an ornamental raised groove 16 which may be any desired shape and location, being illustrated parallel to the periphery of the stamped metal. A piece of channel metal is curved to form a marginal member 17 for the head or circular portion of the back plate 15. Pieces of channel metal 18 and 19 are cut to fit the straight sides of the handle portion 20 of the back plate 15. A smaller short channel member 21 is cut to fit the end of the handle portion 20. The ends of the members 17, 18, 19 and 21 are mitered so as to form close tight joints where they meet. The members 17, 18, 19 and 21 are illustrated as separate pieces but they might be made in a single piece of channel metal, the arms of the channel being cut or mitered at the proper points to allow proper forming into the desired form, or the channel aperture might be made in two or more pieces. For instance members 18, 19 and 21 might be a unit the arms being properly cut or mitered at the ends of 21 to allow the right angled bending necessary. One arm of the channel may be longer than the other if desired. It will be noted that a groove or raised portion 16 has been illustrated on the back plate 15. This makes a marginal ornament for the back or a panel within which may be placed enamel or other ornamental matter.

In order to further ornament the back and let it appear to be in three steps the channel members 17, 18, 19 and 21 may be so formed as to make a figure somewhat larger than the back stamping 15, so that when they are applied to the back stamping 15 it will project around its periphery or substantially on its periphery. This is clearly illustrated in Fig. 2 where it will be observed that the edges of the plate 15 do not extend to the outer sides of the channel members 18 and 19 but engage part of the arms of the channel members only. If desired the channel members may be so formed and placed as to register with the periphery of the plate 15 in whole or in part. Any suitable means may be employed to hold the plates and the channel mem-

bers together. In Fig. 3 X marks 22 have been employed to indicate spot welds which may be used to hold the members together and in order to facilitate their assembly and welding a suitably formed clamping form member may be provided which will hold the several members in their final positions and allow them to be welded or otherwise fastened there.

After the members 15, 17, 18, 19 and 21 have been fastened together a suitably formed plate 23 may be fastened in any suitable way to the free or upper arms of the channel members 18, 19 and 21 to close the handle portion 20 of the device. It will be noted of course that the opening within the channel member 17 is to receive and hold a mirror, brush-head or other device in any suitable well-known way.

The specific forms illustrated are not essential to the present invention, which may be employed in other articles.

I claim as my invention:

1. The method of forming a frame for a hand mirror or the like having a head to hold a mirror or the like and an extending handle portion, comprising stamping from sheet metal a piece approximating in contour the final product, forming a piece of channel metal approximating the size and shape of the head to hold the mirror or the like but somewhat larger, placing the formed channel metal on the corresponding portion of the sheet with one arm of the channel in contact therewith but extending therebeyond throughout the contour, placing pieces of channel metal similarly at the borders of the handle portion with one arm against the sheet and formed at the joints to fit together and to the ends of the formed channel member, holding all the pieces in position with all the channel arms extending inwardly and spot welding the channel pieces to the sheet piece with the channel extending beyond the edge of the sheet piece throughout substantially its entire contour, and fastening a piece of metal to the other arm of the channel members on the handle portion.
45. 2. The method of forming a frame for a hand mirror or the like having a head for holding a mirror or the like and an extending handle portion, comprising stamping from sheet metal a piece approximating in contour the final product, forming a piece of channel metal approximating the size and shape of the head to hold the mirror or the like, placing the formed channel metal on the corresponding portion of the sheet with one arm of the channel in contact therewith, placing pieces of channel metal similarly at the borders of the handle portion and formed at the joints to fit together and to the

ends of the formed channel member, holding all the pieces in position and welding the channel pieces to the sheet piece, and fastening a piece of metal against the other side of the channel members on the handle portion.

3. The method of forming a frame having a head for holding a mirror or the like comprising stamping from sheet metal a piece approximating in contour the final product, forming a piece of channel metal approximating the size and shape of the head to hold the mirror or the like but somewhat larger, placing the formed channel metal on the corresponding portion of the stamped sheet with one arm of the channel in contact therewith but with the base of the channel extending therebeyond throughout the contour, holding the pieces in position and spot welding the channel piece to the sheet piece with the channel extending beyond the edge of the sheet piece throughout substantially its entire contour.

4. The method of forming a frame having a head for holding a mirror or the like and a handle portion, comprising stamping from sheet metal a piece approximating in contour the final product, arranging pieces of channel metal about the handle portion of the stamped piece, placing formed channel metal about the periphery of the stamped sheet with one arm of the channel in contact therewith but extending thereabout throughout the contour, holding the pieces in position and spot welding the channel metal to the sheet piece with the channel extending beyond the edge of the sheet piece throughout substantially its entire contour; and fastening a piece within the borders of the other arm of the channel metal on the handle portion.

5. The method of forming a frame having a head for holding a mirror or the like and a handle portion, comprising stamping from sheet metal a piece approximating in contour the final product, placing formed channel metal about the periphery of the sheet with one arm of the channel in contact therewith, holding the pieces in position and spot welding the channel metal to the stamped sheet piece, and fastening a piece onto the other arm of the channel metal on the handle portion.

6. The method of forming a frame having a head for holding a mirror or the like, comprising stamping from sheet metal a piece approximating in contour the final product, placing formed channel metal on the periphery of the sheet with one arm of the channel in contact therewith, holding the pieces in position, and welding the channel metal to the stamped sheet piece.

ALFRED F. REILLY.

CERTIFICATE OF CORRECTION.

October 19, 1937.

Patent No. 2,096,381.

ALFRED F. REILLY.

It is hereby certified that error appears in the printed specification of the above numbered patent requiring correction as follows: Page 2, second column, line 30, claim 4, for the word "thereabout" read therebeyond; and that the said Letters Patent should be read with this correction therein that the same may conform to the record of the case in the Patent Office.

Signed and sealed this 16th day of November, A. D. 1937.

Henry Van Arsdale,
Acting Commissioner of Patents.
